UNITED STATES PATENT OFFICE.

HENRY P. J. EARNSHAW, OF HYDE PARK, MASSACHUSETTS.

HEATING-BOILER.

No. 861,167.

Specification of Letters Patent.

Patented July 23, 1907.

Application filed March 6, 1905. Serial No. 243,899.

To all whom it may concern:

Be it known that I, HENRY P. J. EARNSHAW, a citizen of the United States, residing at Hyde Park, in the county of Norfolk and State of Massachusetts, have invented an Improvement in Heating-Boilers, of which the following description, in connection with the accompanying drawing, is a specification, like letters on the drawings representing like parts.

This invention relates to a boiler for use in heating systems, and has for its object to provide a novel boiler of this class which is extremely efficient in operation, and which can be used either with steam-heating or hot-water-heating systems.

The particular features wherein the invention resides will be more fully hereinafter described and then pointed out in the claims.

In the drawings, Figure 1 is a vertical sectional view of my improved boiler; Fig. 2 is a front view of the boiler with the setting removed; Fig. 3 is a front view 20 of the adjustable bridge-wall.

The boiler comprises a horizontally arranged boiler-shell 3 having a plurality of flues 4 extending therethrough and circulating water-tubes 5 beneath the boiler-shell and connected thereto at each end. The 25 flues are located entirely in the lower half of the boiler-shell and open at one end into a chamber 6 at the back of the boiler which communicates with the combustion chamber 7, and at their front end into a chamber 8 at the front of the boiler which connects with the smoke-pipe 9. The circulating water-tubes 5 are screwed, nipped or fastened in any suitable way at one end to a front header 10 which is suitably supported on the boiler setting, and at their rear ends to a suitably supported rear header 11. The rear header is connected to 30 the underside of the shell at its rear end by a connection 12.

The front header 10, as stated above, is supported by the boiler setting, and it is arranged to support the front end of the boiler shell 3. For this purpose I have shown 40 a piece of angle-iron 90 secured to the header and on which the front end of the boiler shell rests. Said front header 10 extends horizontally, as shown in Fig. 2, and is of such a depth that its bottom is on substantially the same level as the bottom of the header 11. I 45 have adopted this construction so as to simplify the operation of setting up the boiler.

Rising from the center of the front header is a delivery pipe 13, which is adapted either to deliver to the boiler the steam generated in the circulating pipes 5 or to deliver 50 hot-water to the heating system according to whether the boiler is used in conjunction with a steam-heating system or hot-water heating system. The said delivery-pipe is connected to the upper portion of the shell 3 by means of a nipple 14 of reduced area coincided with the size of the delivery-pipe, and said delivery-pipe has at its upper end an opening which is shown

in Fig. 1, as closed by a plug 15. This plugged-opening is substantially the same size as the delivery-pipe.

When the boiler is used in connection with the steam-heating system the opening is closed by the plug, as shown, and the steam generated in the circulating pipes is returned to the boiler through the nipple 14, and is taken from the boiler by any suitable means into the steam-heating system. The purpose of making the nipple 14 of reduced size is to prevent the water from being driven out of the circulating pipes by the rapid circulation therein faster than it can enter them through the connection 12.

When the boiler is to be used in connection with a hot-water system the plug 15 is removed and the pipe leading to the hot-water system is connected directly to the pipe 13. With this arrangement the hot-water is delivered directly from the delivery pipe 13 into the hot-water system without being returned to the boiler, and since the size of the opening is substantially equal to the pipe 13 a free circulation of the water is provided.

The reason for placing the flues 4 entirely in the lower half of the boiler is so that the water-level in the boiler can be varied within wide limits without uncovering any of the flues and thus running the risk of an explosion.

It is well known that most persons running a house-heating boiler take very little care to maintain the water-level at one point, and therefore, said level is liable to vary considerably. By placing all the flues 4 in the lower half of the shell this variation in the water-level may take place without danger.

Another feature of my improved boiler which I regard of some importance is that the heating surface of the tubular part of the boiler is substantially equal to the heating-surface of the water-tube portion of the boiler. I find that better results are secured by thus proportioning the two heating surfaces.

16 designates the usual ash-pit above which is the grate.

The grate I prefer to use is one comprising grate-bars 17 which extend across the furnace and are supported at their ends in channel-irons 40 running along the sides of the furnace. The top of each grate-bar 17 is provided with ribs 18 extending longitudinally of the furnace, the ribs on each grate bar extending beyond the sides of the grate-bar, as seen in Fig. 1.

42 designates the door leading to the combustion chamber.

I propose to make the bottom 43 of the door-opening inclined, as shown, the inclination extending down to the grate. This construction has the advantage that the front of the grate can be reached by a slice-bar inserted through the door-opening in a way which would not be possible if the bottom of the door-opening were flat or horizontal.

I have herein shown an adjustable bridge-wall 20, which is preferably a piece of cast-iron having the base portion 21 and the upright portion 22, the base-portion resting on the channel-irons 40 and the upright portion 5 forming the bridge-wall proper. The casting 20 is preferably sufficiently heavy so as to retain its adjusted position by its own weight, but I prefer to attach to the base 21 thereof a locking latch 44 which is adapted to engage any one of a number of locking notches 45 in 10 the casting 46. The upright portion 22 of said casting is preferably provided with slots 47 through which the gases are permitted to pass, said slots forming between them fingers 48 which act as a screen to prevent the coal from being thrown over the bridge-wall when it is 15 added to the fire.

For convenience in operating the latch 44 I make one of the slots 47 deeper than the rest and of a width so that a poker may be inserted therethrough, as shown in dotted lines Fig. 1, for raising the latch 44.

20 When it is desired to adjust the bridge-wall the poker is thrust through the slot 47, as above described, and the latch 44 disengaged from its locking notch. By catching the end of the poker either on the end of the latch or against the bridge-wall the latter may be moved 25 toward or from the door of the furnace as desired.

In Fig. 1 the full line position of the bridge-wall shows the latter placed for giving a small grate area, while the dotted-line position shows it placed for giving the maximum grate area.

30 At the rear of the ash-pit 16 is a wall 24 provided with suitable apertures 25 leading to a chamber 26 at the back of the furnace. This chamber is provided with a suitable door 27 by means of which the draft may be regulated, and through which the air for supporting 35 combustion is admitted. When the door 27 is open the air passes first into the chamber 26 where it is partially heated and thence passes through the aperture 25 into the ash-pit from whence it passes through the grate and into the combustion chamber.

40 The object in taking the air into the ash-pit through the back of the furnace instead of through the usual front door 28 leading to the ash-pit and through which the ashes are removed is to provide means for thus partially heating the air before it is delivered to the ash- 45 pit. By means of this construction a material economy in the coal used is effected.

The smoke-pipe 9 which connects with the smoke-chamber 8 at the front of the furnace extends backwardly over the boiler and to the chimney. It has 50 connected thereto a branch-pipe 49 which leads directly into the chamber 6.

50 designates a valve or damper which is adapted to entirely or partially close the pipe 49, as desired, and 51 designates a check-damper leading to the pipe 49. 55 Under normal conditions the damper 50 is closed and the products of combustion pass from the chamber 6 forwardly through the flues 4 into the smoke-chamber 8 and thence to the smoke-pipe 9, and the heat generated may be regulated by the check-damper 51 in the 60 usual manner. In starting a fire, however, the damper

50 will preferably be opened thereby avoiding a direct communication between the combustion chamber and the smoke-chamber. This damper can also be opened in case the flues 4 should become choked from any cause, for even with the flues choked and the damper 65 50 opened it will be possible to generate temporarily sufficient heat by means of the circulating pipes 5.

30 designates a handhold cover at the back of the boiler shell through which the latter may be cleaned out.

The front of the header 10 is provided with a removable cover 31 for giving access to the tubes 5 for cleaning or repairing.

Various changes in the construction of the boiler may be made without departing from the invention.

Having described my invention what I claim as new and desire to secure by Letters Patent is:—

1. In a boiler, a horizontal boiler-shell, a horizontally-arranged front header extending transversely to the shell, said header having on its rear face a ledge to support the front end of the boiler, a rear header, circulating water-tubes connecting the headers, a connection between the rear header and the boiler shell, a delivery-pipe centrally connected to the front header and extending upwardly therefrom, said pipe having at its upper end a T, a nipple connecting said T to the upper part of the boiler, said nipple having a smaller cross sectional area than either the delivery pipe or the connection between the rear header and the boiler.

2. In a boiler, a horizontal boiler-shell having flues extending therethrough, horizontal transversely extending front and rear headers, circulating water-tubes connecting said headers, connections between each header and the boiler-shell, a smoke-chamber at both the front and the rear end of the boiler-shell, each smoke-chamber being connected to the smoke-flue, and a damper controlling the connection between the rear smoke chamber and said flue.

3. In a boiler, a boiler-shell having flues therethrough, circulating water-tubes beneath said shell, front and rear headers to which said tubes are connected, connections between the rear header and the rear end of the boiler-shell, a delivery-pipe connected to the front header, said delivery-pipe having a plugged aperture of substantially the same size as said pipe for connection to a hot-water-heating system, and a nipple of reduced diameter connecting 105 said delivery-pipe with the boiler-shell.

4. In a boiler, a horizontal boiler-shell having flues therethrough, circulating water-tubes beneath the shell and connected thereto, and a movable bridge-wall within the combustion-chamber, said bridge-wall having sufficient 110 weight to retain it in its adjusted position.

5. In a boiler, a combustion chamber, a door opening leading thereto, the bottom of the door opening being inclined, as at 43, an adjustable bridge-wall within said combustion chamber, a horizontal boiler shell above the chamber, said boiler-shell having flues therethrough and circulating water-tubes beneath said shell and connected thereto.

6. In a boiler, a horizontal boiler shell having flues therethrough, circulating water-tubes beneath the shell and connected thereto, a combustion chamber beneath the shell, an adjustable bridge-wall within said combustion chamber, and a locking latch for holding said bridge-wall in its adjusted position, the latter having a slot through which a poker may be inserted for releasing said latch.

In testimony whereof, I have signed my name to this specification, in the presence of two subscribing witnesses.

HENRY P. J. EARNSHAW.
